GAME APPARATUS

Cecil C. Lutes, Bellingham, Wash.

Application July 16, 1936, Serial No. 91,014

4 Claims. (Cl. 273—1)

This invention relates to a game apparatus, and has for one of its objects the production of a simple and efficient game apparatus for use in the playing of the game "LeCoup", and other similar games, embodying skill and chance and which may be easily mastered, requiring at the same time little or no athletic ability.

A further object of this invention is the production of a simple and efficient goal member which may be easily moved to a desired position and which will remain in a set position after once being placed.

A still further object of this invention is the production of a simple and efficient foldable goal member which may be easily and efficiently anchored in position.

Other objects and advantages of the present invention will appear throughout the following specification and claims.

20 In the drawing:

Figure 1 is a plan view of the playing field;
Figure 2 is a vertical sectional view through one of the arches or wickets;

Figure 3 is an enlarged perspective view of the 25 double goal;

Figure 4 is an edge elevation of the double goal in a folded position;

Figure 5 is an enlarged fragmentary side elevation of the double goal;

30 Figure 6 is a perspective view of a single goal;
Figure 7 is a perspective view of a modified form of single goal.

By referring to the drawing, it will be seen that G designates the goal which is specially constructed as will be hereinafter described, and this goal is preferably placed in the center of the court, which court may be varied in size and shape to fit the space available. The court is usually laid out in a square or diamond shape 40 15 to 20 feet to the side, thereby providing four distinct corners. At each of the corners facing the openings in the goal G, is placed an arch or wicket W, and at the other corners are placed posts P. Lines are preferably marked in any 45 suitable or desired manner such as by tape or chalk lines to indicate the bounds of the field and to allow the players to easily determine the plays which are out of bounds. I preferably employ several groups of balls, one group being placed near each arch or wicket W, each group of balls being distinctly colored or marked to allow the different groups to be distinguished, and each group preferably consisting of balls indicated as at B. These groups may be six, eight, or 50 four, as may be desired, and the balls are pref-

erably referred to as "treys". An X-ball indicated by the letter X, preferably solid white, is also employed.

In carrying out my invention, I preferably employ a double goal indicated by the letter G, which double goal is illustrated in detail in Figure 3 and comprises a back or base section 10. The back or base section 10 carries at each end a hinge section 11 which extends transversely across the end of the base or back section as 10 clearly shown in Figure 3, the hinge section 11 carrying at its respective ends rolled portions 12. These rolled portions are offset or spaced from the sides of the base section 10 for the purpose hereinafter described. The double goal also 15 comprises a plurality of side sections 13, each side section carrying a hinge section 14 having rolled portions 15 and anchoring and pintle pins 16 are extended through the rolled portions 12 and 15, and are driven into the ground to constitute an 20 efficient anchoring means for securely anchoring the back or base section 10 against accidental displacement from its selected position. Each side section 13 is provided at its outer end with a substantially U-shaped strap 17 having its outer 25 end slightly spaced from the outer end of the side section 13 to provide a vertically extending channel for receiving the anchoring pins 18, which pins 18 pass between the straps 17 and the ends of the side sections 13 and into the ground 30 for firmly anchoring the side sections in a desired position.

As shown in Figure 3, four of these side sections 13 are employed, which are hingedly connected upon opposite sides to the ends of the back 35 or base section 10, the outer ends of the side sections being free to swing toward or away from each other thereby permitting the side sections to be properly adjusted to the desired angle when the pins 18 may be driven in position to firmly 40 anchor the outer ends of the side sections 13 in a properly set angular position, the outer ends of the side sections 13 being properly spaced to allow the entrance of the balls X and B. As shown in Figure 4, the hinge sections 11 are offset sufficiently to allow the side sections 13 to fold flat and overlap in the manner as shown, thereby 45 permitting the double goal to be conveniently packed and stored to be accommodated in a minimum amount of space. The hinge sections 50 11 at the opposite ends of the back or base section 10 are offset in opposite directions with respect to the ends of the base sections 10 sufficiently to accommodate the thickness of one of the side sections 13 when it lies flat upon the 55

base section 10, as shown in Figure 4, thereby allowing the adjacent overlapping side section 13 to lie in a flat position, as indicated. The hinge sections 11 and 14 and also the straps 17 may 5 preferably be formed of metal, or other suitable material, and the straps 17 preferably overlap the outer ends of the side sections 13 because of their U-shaped structure. The pins 16 and 18 are preferably provided with enlarged heads, as 10 indicated in Figure 5, to overhang the rolled portions 15 of the hinge sections 14 and also the upper edges of the straps 17, in this way providing an efficient anchoring means.

In Figure 6, I have shown a modified form of 15 the invention consisting of a back section 20 and a pair of side sections 21 which are hingedly connected to the back section 20 through the medium of a hinge connection 22, the hinge connection 22 having headed pintle pins 23 which connect the back and side sections together and also extend into the ground to provide an anchoring means. The outer end of each side section 21 is provided with a substantially U-shaped strap 24 having its folded portion slightly spaced 20 from the end of the side section 21 which supports the same, for the purpose of receiving an anchoring pin 25 similar to the anchoring pins 18 previously mentioned, whereby the outer ends of the side sections 21 may be firmly anchored in 25 a proper and desired angular position.

In Figure 7, there is shown a modified form of 30 the invention wherein a back section 26 is illustrated having fixed converging side sections 27 which are spaced at their outer ends to provide a ball-entrance opening 28. This goal, which is clearly illustrated in detail in Figure 7, is of a solid or rigid type wherein the side sections 27 are stationary with respect to the base section or back section 26, and this goal, as shown in Figure 7, is preferably formed of heavy material sufficient to normally remain in a set position when once placed upon the ground or playing field.

It should be understood that certain detail 35 changes in mechanical construction may be employed without departing from the spirit of the invention so long as these changes fall within the scope of the appended claims.

In playing the game two, four, or six players 40 may engage, and in fact any number from two players up may engage in the play. When single goals, such as illustrated in Figure 6, are used, they are placed back to back in the center of the court in the same position as that indicated 45 by the letter G in Figure 1, wherein the double goal is illustrated. The openings in the goal are usually spaced at slightly more than the diameter of two of the balls, or about seven inches and the goals may be colored or marked distinctly to 50 match the colors or markings on the balls. The team balls which are preferably called "treys", are usually marked by single colored stripes on one group, and double stripes or solid color may be used on the other group. As stated above, 55 the X-ball is usually solid white. The object of the game is to accumulate the highest score, and the players proceed as follows:—

The first player places the X-ball down behind 60 his team's arch at one end, such as is shown to 65 the left of Figure 1, and starts the game by driving the X-ball through the arch and into the court. The player will usually try to direct the X-ball past his team's goal, and as much in front of the opponent's goal as possible. The first 70 player of the opposing team will put down one of

his teams treys, a mallet's head diameter behind his team's arch and drive the ball, trying either to knock the X-ball back towards the opponent's goal or to place the treys in position from which a later shot at the X-ball may be made. The 5 second player on the first team will follow by driving in one of his team's treys in like manner. The following players may drive in other treys or play those belonging to their teams already 10 in play as circumstances and their game sense may indicate. Turns at play are alternated between the teams so one team may have more players without creating an advantage.

Rules of play.—A player may not use his mallet on any of the opposing team's treys, nor upon 15 the X-ball, except when putting the X-ball in play. A player may not move any ball, goal, arch, or post, as a preliminary to making a shot nor to give advantage or disadvantage to either side. A trey driven out of bounds as a result of an opponent's shot is out of play and may only be returned to the court by driving it in through the owning team's arch on their turn of play. A trey driven out of bounds as a result of a shot by the team to which it belongs, may be played from 25 where it comes to rest, or called out of play at the owning team's option. When a ball goes into a goal, it is out of play and is removed from the goal and returned to starting position. When the X-ball is goaled, it must be returned to play 30 in the same manner as originally described, by the next player on the next play, or it will go to opponents for an out-of-bounds shot for a minor score on the following play. Intentional violation of the rules forfeits the game to the opponents, and unintentional violation is penalized by loss of a play by the offending team. Shooting on the opponent's turn of play, is further penalized by voiding any score made on the illegal play and putting the trey used out of play. 40

Scores are made by knocking the X-ball into 45 opponent's goal, by driving one of the playing team's treys against it with a mallet, and this counts a major score of ten points. If during a team's turn, the X-ball is knocked or driven 50 out of bounds, the next player on the other team may put it in play by driving in through opponent's arch. If the player drives the ball into 55 opponent's goal on this play it counts a minor score of two points. Should the team entitled 60 to the penalty shot on the X-ball decline it in favor of some other play, then the opponents may put it in play by driving the ball through his own arch. If a player can knock the opponent's trey into any goal by driving one of his 65 own team's treys against it, a trey score of three points results. Sometimes, to prevent opponents from making a major score, it will be found to be good strategy for a player to knock the X-ball into his team's goal by driving his 70 trey against it, this being called a sacrifice and counts three points for the opponent. Other penalty scores of one point for opponent's result when the player drives the X-ball into his own goal when putting the X-ball into play, or when he drives or knocks one of his team's treys into either goal. A ball is not considered in a goal unless every part of it is beyond the goal opening, or the ball is completely within the outer 75 ends of the opening. A total score of fifteen points constitutes a game.

It should be understood that the rules for playing the game may be varied without departing from the spirit of the invention and the above 75

outline is included to describe a typical manner of using the present game apparatus.

Having described the invention, what is claimed as new is:—

5 1. As a new article of manufacture, a goal comprising a straight back section, a pair of side sections, hinge means carried by the extreme ends of said back section for hingedly connecting the side sections being adapted to be selectively swung toward and away from each other and normally lying in an operative position to converge toward their outer ends and providing a 10 restricted entrance opening for the goal, independent anchoring means engaging the hinge means at each end of the back section and the inner ends of the side sections for firmly anchoring the back section 15 and the inner ends of the side sections upon the ground, and independent anchoring means engaging the outer end of each 20 side section for holding the ends of the side sections in selected spaced relation.

2. As a new article of manufacture, a goal comprising a straight back section, a pair of side sections, hinge means carried by the extreme 25 ends of said back section for hingedly connecting the side sections being adapted to be selectively swung toward and away from each other and normally lying in an operative position to converge toward their outer ends and providing a 30 restricted entrance opening for the goal, independent anchoring means engaging the hinge means at each end of the back section and the inner ends of the side sections for firmly anchoring the back section and the inner ends of the 35 side sections upon the ground, independent anchoring means engaging the outer end of each side section for holding the ends of the side sections in selected spaced relation, the end sections being foldable flat upon the back section whereby the end sections may snugly lie against the back section when folded, and said anchoring means having enlarged heads overhanging the hinge means for preventing upward movement 40

of the sections with respect to the anchoring means.

3. As a new article of manufacture, a goal comprising a straight back section, a pair of side sections, hinge means carried by the extreme 5 ends of said back section for hingedly connecting the side sections being adapted to be selectively swung toward and away from each other and normally lying in an operative position to converge toward their outer ends and providing a 10 restricted entrance opening for the goal, independent anchoring means constituting removable pintles for said hinge means at each end of the back section and the inner ends of the side sections for firmly anchoring the back section 15 and the inner ends of the side sections upon the ground, and independent anchoring means engaging the outer end of each side section for holding the ends of the side sections in selected 20 spaced relation.

4. A game apparatus of the class described comprising a straight back section, a plurality of side sections, a hinge section secured to each end of said back section, hinge sections secured to the inner ends of said side sections, some of 25 said side sections extending in one direction with respect to the base section, and other of said side sections extending in the opposite direction, anchoring pins passing through said hinge sections and constituting a pintle therefor for 30 hingedly connecting the back and side sections and holding the inner ends of said side sections firmly anchored upon the ground, anchoring means engaging the outer ends of said side sections 35 for anchoring the outer ends of said side sections in selected spaced relation and holding the outer ends of said side sections firmly anchored upon the ground, the hinge sections carried by the back section being offset laterally in opposite directions whereby the side sections 40 may be folded flat against the back section when the goal is in a knockdown position.
